ELECTRIC COUPLING SYSTEM

Arthur G. Manke, Schenectady, N. Y., assignor
to General Electric Company, a corporation of
New York

Application April 10, 1944, Serial No. 530,346

8 Claims. (Cl. 250—8)

My invention relates to electric coupling systems and, more particularly, to beat frequency oscillator transformers of the type utilized in radio reception systems.

In radio telegraph reception systems, it is customary to render an unmodulated carrier wave audible by beating with the received carrier, or with a carrier of suitably reduced intermediate frequency, local oscillations of nearly equal frequency generated in a beat frequency oscillator. One known manner of injecting the local oscillations from the beat frequency oscillator into the carrier wave channel is by coupling to the grid circuit of an intermediate frequency amplifier stage preceding the second detector. For this purpose, the intermediate frequency transformer may be provided with a third winding connected to the beat frequency oscillator. In any such arrangement, it is desirable that the oscillations in the transformer grid coil from the beat frequency oscillator be at least equal in amplitude to the oscillations of carrier frequency in the same coil in order fully to load the output stages of the receiver. On the other hand, care must be exercised that the amplitude of oscillations from the beat frequency oscillator is not so great as to operate the automatic volume control circuits associated with subsequent stages of the receiver.

It has been found that the elements of the beat frequency transformer must be rigidly mounted in fixed relation during manufacture to ensure frequency stability and reliability of operation. Furthermore, since it is necessary to maintain maximum suppression of oscillations at the frequency of the beat frequency oscillator in other parts of the receiver, it is necessary that the oscillator coil and the grid coil remain tuned accurately to the frequency of the beat frequency oscillator. It is, therefore, impractical to control the amplitude of local oscillations in the grid coil either by varying the coil tuning or the coil coupling.

Accordingly, it is a general object of my invention to provide a new and novel coupling system and method for beating together electric oscillations of different frequencies.

Another object of my invention is the provision of a new and novel method and means for adjusting the amplitude of electric oscillations introduced into a circuit from one source without appreciably affecting oscillations of nearly equal frequency induced in the same circuit from another source.

It is a more specific object of my invention to provide means for adjusting the amplitude of

oscillations induced in the grid coil of a beat frequency transformer from the beat frequency oscillator without changing the tuning, coupling or spacing of either the grid coil or the oscillator coil.

5 My invention will be more fully understood and its objects and advantages further appreciated by referring now to the following detailed specification taken in conjunction with the accompanying drawing in which Fig. 1 is a schematic circuit diagram of a radio receiving apparatus embodying my invention; and Fig. 2 is a side elevation, partly in section, of a practical embodiment of the combined beat frequency oscillator and intermediate frequency transformer of the type illustrated schematically at Fig. 1.

Referring now to the drawing, and particularly to Fig. 1, I have shown a radio telegraph receiving apparatus comprising an antenna 10 coupled to a signal channel comprising a plurality of stages of amplification 11 and 12 and a detector 13. Preferably, the receiving apparatus is of the superheterodyne type and comprises also a suitable number of stages of radio frequency amplification, a local oscillator and a mixer for converting the carrier wave to an intermediate frequency of predetermined fixed value, and a suitable number of stages of intermediate frequency amplification preceding the stage 11. These preceding stages 20 of the receiving apparatus are shown in block form and identified by the reference numeral 14. It will therefore be understood that that portion of the signal channel represented by the reference numeral 14 supplies to an intermediate frequency transformer 15 an unmodulated carrier wave of predetermined fixed intermediate frequency.

Through the transformer 15 the intermediate frequency carrier wave is impressed upon a control grid 16 of an electron discharge device 17 in 40 the amplifying stage 11. The discharge device 17 comprises a cathode 17a, a screen electrode 17b and a plate 17c. The cathode 17a is connected to ground through a grid leak resistor 17c and bypass condenser 17d. The plate 17c is connected to 45 a resonant output circuit comprising a transformer winding 18 of variable inductance and a condenser 19 connected in parallel circuit relation. The transformer winding 18 is the primary winding, or plate coil, of a combined beat frequency oscillator and intermediate frequency transformer 20. The transformer 20 is also provided with a variable inductance secondary winding 21 closely coupled to the winding 18 and tuned to resonance at a desired intermediate frequency by a capacitor 22 and con-

ected between the cathode 23 and the control grid 24 of an electron discharge device 25 in the amplifying stage 12. The cathode 23 is connected to ground through a grid leak resistor 23a and a by-pass condenser 23b. The discharge device 25 includes also a plate 26 connected to an intermediate frequency coupling transformer 27 having primary and secondary windings 28 and 29 tuned to resonance at the intermediate frequency by parallel-connected capacitors 30 and 31, respectively. The discharge device 25 is preferably provided also with a screen electrode 26a connected to a suitable source of positive unidirectional potential, as shown.

The secondary winding 29 of the intermediate frequency transformer 27 supplies oscillations to the diode detector circuit 13. The diode detector comprises the anode 32 and cathode 33 of a double diode electric discharge device 34 connected in series circuit relation with a load resistor 35 and a decoupling resistor 36 across the terminals of the transformer winding 29. The resistors 35 and 36 are shunted by a capacitor 37 for bypassing carrier and other high frequency oscillations. The cathode 33 of the diode 34 is grounded for high frequency potentials through a condenser 38 and is maintained at a positive unidirectional potential with respect to ground by a cathode resistor 39. The resistor 39 is connected between the cathode 33 and ground and across a suitable source of unidirectional potential 40 through a resistor 40a. Audio frequency voltages appearing across the load resistor 35 are supplied to audio frequency amplifiers and thence to a suitable signal reproducing device, such as a loud speaker, head phones or the like, all indicated in block form upon the diagram by the reference numeral 41.

To provide automatic volume control, the gain of one or more preceding stages of the receiver is controlled by a bias potential derived from the output of the intermediate frequency transformer 27 through a diode rectifier comprising a second anode 42 and the cathode 33 of the electric discharge device 34. The anode 42 is connected to one terminal of the transformer 27 through a coupling condenser 43 and a load resistor 44 is connected between the anode 42 and ground. The negative bias potential appearing across resistor 44 is supplied through a suitable decoupling resistor 45 and filter condenser 45a to control the gain of a preceding stage of the receiver.

It will be noted that the cathode biasing resistor 39 associated with the double diode discharge device 34 has no appreciable effect upon the audio frequency detection circuit, but provides for "delayed" automatic volume control operation. The "delayed" operation of the volume control circuit results from the fact that the automatic volume control section of the double diode 34 is not rendered conductive until the carrier wave exceeds a predetermined amplitude sufficient to raise the potential of the anode 42 above the positive bias potential of the cathode 33. It is only when the anode 42 of the double diode 34 is conducting that a volume control bias is developed across the resistor 44. By this arrangement operation of the volume control circuit by the beat frequency oscillations is prevented.

Referring now again to the beat frequency transformer 20, it may be noted that the unmodulated carrier wave appearing in the transformer primary winding 18 is modulated by beat-

ing with it electric oscillations of a nearly equal frequency supplied by a beat frequency oscillator 50. The beat note is then rendered audible by detection in the circuit 13. In order to modulate the received carrier wave the transformer 20 is provided with a tertiary winding 51 tuned to resonance at a desired frequency by means of a variable capacitor 52 and connected through capacitors 53 and 54, respectively, to the plate 55 and control electrode 56, respectively, of an electron discharge device 57. The winding 51 is closely coupled to the winding 21 and loosely coupled to the winding 18. The cathode 58 of the discharge device 57 is connected directly to an intermediate point of the coil 51 and through a grid biasing resistor 59 to the control grid 56. The anode 55 of the discharge device 57 is connected through a decoupling resistor 60 to a suitable source of positive potential indicated as B+. It will now be evident that the electron discharge device 57 and the tuned circuit comprising the transformer winding 51 and tuning condenser 52 constitute an oscillator of the well-known Hartley type and function to generate in the coil 51 electric oscillations of a desired frequency.

It will, of course, be understood that I have shown the particular oscillator 50 by way of illustration only, and that my invention is not limited thereto but contemplates any suitable source of local oscillations of desired frequency coupled to the grid coil 21. If desired, the oscillator triode 57 and the double diode 34 may be built within a single discharge envelope. In such case, the cathodes 33 and 58 shown on the drawing would be the single cathode of the combination tube, so that the oscillator cathode, as well as the diode cathode, would be biased positively with respect to ground by the resistor 39.

Preferably, the beat frequency transformer windings 18, 21, and 51 and their associated tuning condensers 19, 22, and 52 are physically positioned within a unitary shielding enclosure illustrated schematically at Fig. 1 by the reference numeral 63. At Fig. 2, I have shown a cross-sectional view of such a transformer mounted within a metallic casing 63 and comprising a suitable fixed support, such as a tube 64 of insulating material, carrying the plate coil 18 and grid coil 21 and a similar support 65 carrying the oscillator coil 51. The insulating supporting tubes may, by way of example, be mounted in fixed insulating supporting plates 64a and 65a. Adjustable iron core members 66 and 67 for the coils 18 and 21, respectively, are disposed in the hollow ends of the tube 64. The iron cores 66 and 67 may be arranged threadingly to engage the ends of the casings 63 so that their positions within the coils 18 and 21 may be adjusted to control the coil inductance. It will be understood that, while the tuning condensers 19, 22, and 52 are not shown at Fig. 2, they are preferably mounted also within the casing 63 to provide optimum shielding of all circuits associated with the beat frequency oscillator 50 from other parts of the receiving apparatus. By this positioning of the coils upon the separate supports 64 and 65, the coils 18 and 51 are both closely coupled to the coil 21 and loosely coupled to each other.

To ensure reliability and frequency stability in operation, it is necessary that the windings 18, 21 and 51 and the supporting members 64 and 65 of the beat frequency transformer shown at Fig. 2 be rigidly and immovably mounted within the casing 63. In manufacture, the spacing of the supporting members and the spacing of the

coils upon the supports is controlled to a high degree of accuracy. However, even with careful control of the spacing, very substantial variations in coil coupling are frequently encountered. Such variations affect the oscillator voltage induced in the grid coil. This induced voltage must be kept within certain limits because, while it is desirable to obtain 100 per cent modulation of the received carrier waves so that the output stages of the receiver will be fully loaded by the signal wave, it is undesirable that the voltage induced in the grid coil 21 from the beat frequency oscillator coil 51 be so large that the automatic volume control circuit is brought into operation in the presence of a carrier wave of desired amplitude. It is, therefore, desirable to provide means for controlling the amplitude of the beat frequency oscillations induced in the grid coil 21, so that these oscillations will not operate the automatic limiting circuit but are slightly greater in amplitude than the oscillations of carrier frequency induced in the coil 21 from the coil 18. While it is possible to control the amplitude of oscillations in the grid coil 21 from the beat frequency oscillator 50 by detuning the resonant circuit 21, 22, this is undesirable because maximum suppression of undesired responses from the beat frequency oscillator 50 is attained when the resonant circuit of the oscillator and the resonant circuit 21, 22 are both tuned to substantially the frequency of the oscillations supplied by the oscillator 50. Furthermore, as previously pointed out, the amplitude of oscillations induced in the coil 21 from the coil 51 cannot be controlled by varying the coupling of the coils by reason of the fact that the coils are fixedly mounted within the transformer casing 63.

Preferably, the grid coil tank circuit 21, 22 is tuned approximately to the second harmonic of the fundamental frequency of the oscillator 50, so that the beat frequency oscillations mixed with the carrier wave in the transformer 20 have double the fundamental frequency of the local oscillations generated. This is desirable in order to prevent absorption of the intermediate frequency signals due to the beat frequency oscillator tank circuit 51, 52. Furthermore, operation at a harmonic of the beat frequency oscillator reduces the tendency of the oscillator 50 to pull into step with the intermediate frequency oscillations. The beat frequency oscillations are injected into the signal channel at a point preceding the amplifier 25, as into the transformer 20, so that the intermediate frequency amplifier 25 may be used to amplify the beat frequency oscillations along with the intermediate frequency carrier. In this manner a beat frequency oscillator of relatively small power may be used.

According to my invention, the amplitude of oscillations coupled into the grid coil 21 from the beat frequency oscillator 50 is controlled by a means physically separate from both the tuned grid circuit 21, 22 and the tuned beat frequency oscillator circuit 51, 52. For this purpose, I utilize the adjustable iron core 66 of the plate coil 18. By varying the tuning of the resonant circuit 18, 19 with respect to the resonant circuit 21, 22, I find that the apparent impedance reflected back to the tuned grid circuit 21, 22 from the tuned plate circuit 18, 19 may be varied in order very effectively to control the amplitude of oscillations induced in the coil 21 from the coil 51 without varying the tuning, coupling or spacing of the coils 21 and 51. For this purpose, the

coils 18 and 21 are preferably coupled slightly over their critical value, so that slight detuning of the resonant plate circuit 18, 19 with respect to the resonant grid circuit 21, 22 has little appreciable effect upon the amplitude of the carrier wave oscillations induced in the coil 21 from the coil 18.

It is contemplated that both the carrier wave supplied to the transformer winding 18 and the oscillations supplied from the oscillator 50 are of high frequency in relation to the low audio difference frequency appearing across the detector load resistor 35. By way of example, the intermediate carrier wave frequency may be 160 kilocycles per second, while the second harmonic frequency supplied to the transformer 20 from the local beat frequency oscillator 50 may be 159 kilocycles per second. The detected audio frequency is thus 1000 cycles per second. The oscillator fundamental frequency to which the coil 51 is tuned is 79.5 kilocycles per second. Preferably the grid coil 21 is tuned to the nominal intermediate frequency of 160 kilocycles per second. The tuning is sufficiently close to the oscillator 20 second harmonic at 159 kilocycles to respond strongly to the second harmonic without interference from other harmonics. The plate coil 18 may then be normally tuned to 160 kilocycles per second and subsequently slightly detuned with respect to the coil 21 if it is desired to increase the strength of the beat frequency signal. If it is desired to permit decrease of the beat frequency signal strength as well as an increase, the coil 18 may be normally tuned slightly on either side of the 160 kilocycles to which the coil 21 is tuned. In this latter case the beat frequency signal is increased as the coil 18 is further detuned and decreased as the tuning of the coil 18 approaches the resonant frequency of the coil 21. It is also possible to tune the grid coil 21 to the oscillator frequency of 159 kilocycles per second or to some frequency between 159 kilocycles and the intermediate frequency of 160 kilocycles, while the plate coil 18 is normally tuned to 160 kilocycles. In this case also, the strength of the beat frequency signal may be controlled by bringing the frequency of the coil 18 toward or away from that of the coil 21 to control the reflected impedance.

In any case, in order to maintain a minimum of disturbance, it is desirable that the tuning of the plate coil 18 with respect to the grid coil 21 be carried out on the opposite side of the intermediate frequency from that to which the oscillator coil 51 is tuned. That is, if the coil 51 is tuned to 79.5 kilocycles per second, as in the above example, the coil 21 to 160 kilocycles per second, and the coil 18 normally to 160 kilocycles per second, the resonant frequency of the coil 18 should be increased rather than decreased to increase the beat frequency signal. By way of illustration, it has been found possible to control the amplitude of the oscillations induced in the coil 21 from the oscillator coil 51 over a range of approximately 2:1 without appreciably affecting the transmission of oscillations of carrier wave frequency through the transformer.

While I have illustrated only one preferred embodiment of my invention by way of illustration, many modifications will occur to those skilled in the art, and I therefore wish to have it understood that I intend in the appended claims to cover all such modifications as fall within the true spirit and scope of my invention.

What I claim as new and desire to secure by Letters Patent of the United States is:

1. In an electric coupling system comprising a pair of resonant circuits in closely coupled inductive relation and a source of electric oscillations closely coupled to only one of said resonant circuits, the method of controlling the amplitude of oscillations from said source in said one resonant circuit which comprises varying the tuning of the other of said resonant circuits with respect to said one resonant circuit.

2. In an electric coupling system comprising a pair of resonant circuits in closely coupled inductive relation and a source of electric oscillations of predetermined frequency closely coupled to only one of said resonant circuits, the method of modulating a carrier wave of another frequency which comprises impressing said carrier wave upon said one resonant circuit, coupling into said one resonant circuit oscillations from said source, and varying the tuning of said other resonant circuit to control the amplitude of oscillations from said source in said one resonant circuit.

3. In an electric coupling system comprising a pair of resonant circuits in closely coupled inductive relation tuned to substantially the same frequency and a third resonant circuit closely coupled to only one of said pair of resonant circuits and tuned to the frequency of said one resonant circuit, the method of modulating electric oscillations of one high frequency with oscillations of a second high frequency which comprises inducing oscillations at said one frequency in said one resonant circuit from the other of said pair of resonant circuits, coupling oscillations at said second frequency from said third resonant circuit to said one resonant circuit, and varying the tuning of said other resonant circuit to control the amplitude of oscillations of said second frequency in said one resonant circuit without appreciably affecting the amplitude of oscillations of said one frequency.

4. In an electric coupling system comprising a pair of resonant circuits in closely coupled inductive relation with a third resonant circuit and loosely coupled in inductive relation with each other, the method of modulating electric oscillations of one high frequency with oscillations of a second high frequency which comprises tuning said third resonant circuit and one of said pair of resonant circuits to a first high frequency, tuning the other of said pair of resonant circuits to a second high frequency, inducing a voltage at said one high frequency in said third resonant circuit from said one resonant circuit, inducing a second voltage at said second high frequency

5 in said third resonant circuit from said other resonant circuit, and slightly detuning said one resonant circuit with respect to said third resonant circuit to control the amplitude of said second induced voltage without appreciably affecting the amplitude of said first induced voltage.

5. In an electric coupling system comprising a pair of loosely coupled resonant circuits each arranged to induce electric oscillations in a third resonant circuit closely coupled to each of said pair of circuits, the method of controlling the amplitude of oscillations induced in said third circuit from one of said pair of resonant circuits which comprises varying the tuning of the other of said pair of resonant circuits.

6. In combination, a signal channel for transmitting a carrier wave, said channel comprising a pair of resonant circuits in closely coupled inductive relation and tuned to different frequencies nearly equal to the frequency of said carrier wave, and additional means for coupling into only one of said resonant circuits electric oscillations at substantially the resonant frequency of said circuit, the amplitude of said oscillations being determined by the relative detuning of said pair of resonant circuits.

7. In combination, a signal channel arranged to transmit a carrier wave, said signal channel comprising a pair of resonant circuits in closely coupled inductive relation, a source of electric oscillations having a frequency different from the frequency of said carrier wave closely coupled to only one of said resonant circuits, said one resonant circuit being tuned substantially to the frequency of oscillations from said source, and means for controlling the tuning of the other of said resonant circuits with respect to said one resonant circuit to control the amplitude of oscillations from said source in said one resonant circuit.

8. A radio receiving apparatus comprising a signal channel arranged to transmit a high frequency carrier wave, said signal channel comprising a pair of resonant circuits in closely coupled inductive relation tuned to substantially the frequency of said carrier wave, a source of electric oscillations having a frequency substantially equal to the resonant frequency of one of said pair of tuned circuits and including a third resonant circuit closely coupled inductively to only said one resonant circuit, and means for varying the tuning of the other of said pair of resonant circuits to control the amplitude of oscillations induced in said one resonant circuit from said source.

ARTHUR G. MANKE.
